UNITED STATES PATENT OFFICE.

CHARLES E. RILEY, OF CHARLESTOWN, INDIANA.

CRYSTAL-DETECTOR HOLDER.

Application filed May 18, 1925. Serial No. 31,157.

This invention relates to a crystal detector and more specifically to a holder for a crystal and has for its primary object the construction of a holder including a plurality of contact points, two or more being in contact with the crystal at all times thereby assuring perfect electrical connections.

An object of the invention is the construction of a holder in which contact points are so arranged that a plurality of points will engage the crystal irrespective of the shape of the crystal.

A feature of my invention is the construction of a holder wherein various size pieces of crystal may be accommodated and accuracy of contact assured.

With these and other objects in view, the invention will be better understood from the following description taken in connection with the accompanying drawings, wherein:

Fig. 1 is a plan view.

Fig. 2 is a top plan view partly in section.

Fig. 3 is an enlarged longitudinal sectional view on the line 3—3 of Fig. 1.

Fig. 4 is an enlarged cross-sectional view on the line 4—4 of Fig. 1.

Again referring to the drawings illustrating one of the many constructions of my invention, the numeral 1 designates a base having attached thereto a supporting plate 2. A plurality of contact plates 3 are provided of different areas and connected together by the bolts 4 into a right hand set 5 and a left hand set 6. Each contact plate is provided with a plurality of contact points 7 and the points of one plate are arranged in staggered relation with the points of the other plate and also in overlapped relation so as to provide a valley or a tapering recess 8 between the sets of plates. To complete the invention I provide the binding posts 9 and 10 connected to the sets of plates.

From the foregoing description taken in connection with the accompanying draw-

ings it will be seen that any irregular shape of crystal of any size may be deposited in the tapering recess and contact with two or more points positively assured. This multiplicity of points of contact assures perfect electrical conductivity and assures the efficient operation of the instrument. A very important feature of my invention is that it is not necessary to bring about sensitive accurate engagement between the point and the crystal as the gravitational action of the piece of crystal will enable the crystal to come to rest in its most advantageous position.

It is, of course, to be understood that the exact construction of the plates and the shape of the contact points may be changed in various ways and therefore I do not desire to be limited in any manner except as set forth in the claims hereunto appended.

Having thus described my invention, what I claim is:

1. A crystal detector holder including a supporting member, a plurality of superposed contact plates of different areas carried by the supporting member and provided with crystal engaging edges arranged in overlapping relation providing a tapered recess within which a crystal is confined, and means for connecting the contact plates together in sets.

2. A crystal detector holder comprising a base, a plurality of contact plates electrically connected in sets, said plates having contact points arranged in overlapping staggered relation.

3. A crystal detector holder comprising a base, a plurality of contact plates electrically connected in sets, said plates having contact points arranged in overlapping staggered relation, said contact points forming a tapering recess therebetween.

In testimony whereof I affix my signature.

CHARLES E. RILEY.
